UNITED STATES PATENT OFFICE.

WILLIAM A. FORCE, JR., OF KEW GARDENS, NEW YORK, ASSIGNOR TO WM. A. FORCE & COMPANY, INC., OF NEW YORK, N. Y., A CORPORATION OF NEW YORK.

HAND-STAMP FRAME.

Application filed September 8, 1922. Serial No. 587,012.

To all whom it may concern:

Be it known that I, WILLIAM A. FORCE, Jr., a citizen of the United States, residing at Kew Gardens, Richmond Hill, in the county of Queens and State of New York, have invented certain new and useful Improvements in Hand-Stamp Frames, of which the following is a specification.

My invention relates to improvements in hand stamps and particularly to those to be used in making imprints in bound volumes. It is my object to so construct the frames of such hand stamps that impressions can be made close to the left hand edge of the right hand page of bound books, as in entering dates in books of account.

Heretofore the frame and bottom plate of a hand stamp have prevented the printing mechanism reaching very close to the left hand edge of a right hand page of a bound book because of the thickness of the binding and the piling up of the left hand sheets and impressions had to be made at some distance from said edge.

I have devised a special frame for such work which does not interfere with the use of the hand stamp in the regular manner and in the drawing have shown it applied to a hand stamp dater. Fig. 1 is a view of the front of my improved hand stamp; Fig. 2 a side view thereof; and Fig. 3 a sectional view of the structure of Fig. 1 on the line 3—3 thereof in the direction of the arrows.

The invention resides particularly in the construction of the frame and bottom plate of the hand stamp. The substantially U-shaped frame is cut short on one leg 1 and left regular length on the other leg 2. The bottom plate 3 is secured to the long leg 2 at one end, extends toward the short leg 1

and is shorter than the full width of the frame as shown in Figs. 1 and 3.

The free end of the bottom plate 3 is braced to the leg of the frame by a strut 4 so that the stamp frame will not yield 45 when used.

The usual printing wheels 5, operated by a plunger 6 and a knob 7 are mounted in the frame and an ink pad 8 is provided to supply ink to the type wheels.

It is apparent that the hand stamp can be used to make impressions in the ordinary places but when the left or bound edge of a right hand page of a bound book is to be imprinted the stamp frame can be pushed up 50 against the bound book as shown in Fig. 1 with the folds of the left hand sheets entering the space between the short leg 1 and the short bottom plate 3 so that the impression can be made very close to the bound edge 55 of the sheet to be printed upon.

I claim:—

1. A frame for hand stamps comprising a substantially U-shaped frame adapted to contain printing mechanism, one leg of said frame being shorter than the other, and a bottom plate secured to the long leg of the frame and extending toward the short leg.

2. A frame for hand stamps comprising a substantially U-shaped frame adapted to 70 contain printing mechanism, one leg of said frame being shorter than the other, a bottom plate secured to the long leg and extending towards the short leg and a strut extending from the bottom plate to a frame 75 leg.

In testimony whereof I have affixed my signature.

WILLIAM A. FORCE, JR.
